UNITED STATES PATENT OFFICE.

ARTHUR W. SWANBERG, OF MINNEAPOLIS, MINNESOTA.

PROCESS OF INCREASING THE EFFICIENCY OF HYDROCARBON LIQUIDS AND THE MATERIAL FOR EFFECTING SUCH RESULTS.

1,092,461.

Specification of Letters Patent. Patented Apr. 7, 1914.

No Drawing.

Application filed June 5, 1912. Serial No. 701,798.

To all whom it may concern:

Be it known that I, ARTHUR W. SWANBERG, a citizen of the United States, residing at Minneapolis, in the county of Hennepin 5 and State of Minnesota, have invented certain new and useful Improvements in Processes of Increasing the Efficiency of Hydrocarbon Liquids and the Material for Effecting Such Results; and I do hereby declare 10 the following to be a full, clear, and exact description of the invention, such as will enable others skilled in the art to which it appertains to make and use the same.

My invention has for its object to provide 15 an improved process for increasing the thermo and light producing efficiency of low grade hydro-carbon oil, such as low grade gasoline and other hydrocarbon fluids such, for instance, as city gas.

20 To the above ends, the invention consists of the novel manner of treatment hereinafter described and defined in the claims.

The invention will be made clear from the following statement.

25 Take, for instance, one gallon of low grade gasoline or naphtha and add thereto, one ounce of a powder compound from the following materials, approximately in the proportions stated, to-wit: seven parts of naphthalene ($C_{10}H_8$) and three parts of 30 anthracene ($C_{14}H_{10}$). Where extremely high illuminating or heating efficiency, or explosive power is desired, add, also, one ounce of a liquid made up, one-half of sulfuric 35 acid and one-half of wood alcohol.

In actual practice, I have found that the heating efficiency, the illuminating efficiency, and the explosive power of hydro-carbon liquid such as gasoline and naphtha will be very greatly increased by the treatment and 40 addition of the parts thereto, above described. The materials added to the hydro-carbon liquid do not increase the cost thereof very greatly, and hence there is a resulting 45 economy in the use of the hydrocarbon liquid thus treated.

What I claim is:

1. The process of increasing the efficiency of hydro-carbon liquids which consists in first adding thereto, powdered naphthalene 50 and powdered anthracene, and in thereafter adding thereto, sulfuric acid and wood alcohol.

2. A hydro-carbon liquid having therein naphthalene, anthracene, sulfuric acid, and 55 wood alcohol in approximately proportions of one gallon of said hydro-carbon liquid, one ounce of powdered material composed of seven parts of naphthalene and three parts of anthracene, and one ounce of the liquid 60 made up of one-half sulfuric acid and one-half of wood alcohol.

In testimony whereof I affix my signature in presence of two witnesses.

ARTHUR W. SWANBERG.

Witnesses:

HARRY D. KILGORE,
F. D. MERCHANT.
